ARCHIE REXALD WOLFE, OF SUMMIT, NEW JERSEY

NONSCREW PLUG

Application filed March 6, 1929. Serial No. 344,890.

(GRANTED UNDER THE ACT OF MARCH 3, 1883, AS AMENDED APRIL 30, 1928; 370 O. G. 757)

My invention relates to improvement in electric plugs adapted to engage and make electrical connection with the standard screw rim socket, and the objects of the improvements are, first, to produce a non-screw electric plug that can be instantly attached and electrically connected to the standard screw rim socket without screwing said plug or socket and that can be instantly detached and electrically disconnected from said socket without screwing the latter or said plug; second, to provide in a non-screw plug a means for elevating its center contact a limited distance after said plug is attached to the screw rim of said socket and means for depressing said center contact before said plug can be inserted within or attached to said screw rim; third, to provide in a non-screw plug an elevating and depressing means for elevating and depressing its center contact, an attaching and detaching means for attaching and detaching the screw rim of the standard socket without screwing said plug or socket, and a single means on the outside of said plug for operating both said elevating and depressing means and attaching and detaching means; fourth, to provide in a non-screw plug a receptacle means for attaching and electrically connecting any standard electric plug attachment; fifth, to produce a non-screw plug readily designed with binding posts and insulated base cap for connection directly with the leads of portable electric lamps and other portable electric apparatus; and sixth, to produce a non-screw electric plug that is adapted to be used in place of the standard screw rim plug on portable electric apparatus such as vacuum cleaners, toasters, waffle irons, laundry irons, portable lamps, etc., and that will save the American public millions of dollars worth of time each year now wasted while screwing the standard screw rim plug into and out of the standard screw rim socket.

One form of my invention, a non-screw plug provided with receptacles for receiving and electrically connecting the standard plug attachment is described in this specification and illustrated in the accompanying draw-

ing, in which, Fig. 1, is a view of the invention from a point vertically above the center of its center contact and showing said plug in the contracted position; Fig. 2, is a vertical sectional view on the broken line 1 1, Fig. 1 showing the fastening elements in contracted position; Fig. 2a is a similar view showing the fastening elements in expanded position; Fig. 3, is a vertical sectional view on the broken line 2 2, Fig. 1; and Fig. 4, is a view of the bottom.

Similar numerals refer to similar parts throughout the several views.

In this particular form of the invention I prefer to illustrate the metal arms 1, and 2, as joined together at their lower ends forming a U shaped spring the tension of which tends to separate said arms at all times. The lower end of said spring is secured to the lower section 3, of the insulation body and within the cavity 4, of the latter by the machine screw 5, which is countersunk into the bottom of said section 3. Said arms 1, and 2, are provided with the contacts 6, and 7, respectively, which are threaded to mesh with the threads on the interior of the screw rim of the standard socket.

The middle section 8, and the upper section 9, of the insulation body, and said lower section 3, are rigidly clamped and secured together by the threaded tie bolts 10, and 11, which pass through apertures provided in said sections 9, 8, and 3, and are secured by the threaded nuts 12, and 13, respectively, which are countersunk into the bottom of said section 3.

The apertures 14, and 15, in said section 8, accommodate said arms 1, and 2, respectively, and limit the distance the latter can expand or be separated from each other, and the slots 16, 17, and 18, in said section 9, accommodate said arms 1, and 2, and contacts 6, and 7, and limit the distance the latter can be contracted or moved toward each other.

The metal center contact 19, is rigidly affixed to the reciprocating metal center contact rod 20, which projects downward through apertures provided in said sections 9, and 8, and into said cavity 4, and is provided with

the slotted aperture 21, and the metal flange 22, which is contracted into and secured in a circular groove in said rod 20. The latter also passes through a slotted aperture near the upper end and a circular aperture near the lower end of the metal center contact spring 23, which is secured to the upper side of said middle section 8, by the machine screw 24, and nut 25, which also secure the spring 23, to the under side of said section 8. The force of said spring 23, is applied between the underside of the flange 22, and said section 8, thus tending to keep said rod 20, in the elevated position at all times, and permanent electrical connection is completed from said rod 20, through said flange 22, spring 23, screw 24, and nut 25, to said attachment contact 26. The attachment aperture 27, accommodates said contact 26; and the attachment aperture 28, in said lower section 3, accommodates the spring attachment contact 29, one end of which is electrically connected and secured to said arms 1, and 2, by said screw 5.

25 The arm 1, is enlarged in width near its middle portion and is provided with the aperture 30, which accommodates the insulation sleeve 31, which is secured to the metal cam lever 32, and insulates the latter from said arm 1, and the metal radial arm 33, which is pivoted or hinged to said arm 1, by means of the axis tip 34, which is retained within the axial aperture 35, in said arm 1. One end of said sleeve 31, is reduced in diameter and engages an aperture in the upper end of said radial arm 33. The latter is secured to said sleeve 31, by means of the insulated button 36, which is secured by machine thread to one end of said cam lever 32. The other end of 40 the latter projects into the slotted aperture 21, in said center contact rod 20.

The insulated button 37, is secured to the metal screw 38, which is secured to said arm 2.

The cavity 39, in the lower end of said upper section 9, accommodates said flange 22, spring 23, nut 25, and the upper end of said screw 24.

50 In the practical operation of this form of the invention, the buttons 36, and 37, are grasped and manually depressed by thumb and forefinger of one hand. As the tension of the spring 23, is considerably weaker than that of the arms 1, and 2, the button 36, is depressed first, which moves the sleeve 31, cam lever 32, and radial arm 33, as a unit on the axis of the latter depressing the inner end of said cam lever 32, and consequently the center contact rod 20, and contact 19, a limited distance until said radial arm 33, is 55 fully depressed against said arm 1. Sufficient additional pressure on said buttons 36, and 37, contracts said arms 1, and 2, a maximum distance within the slots 17, and 18, respectively. The mechanism of said plug is 60 now in the full contracted position as shown

in Figs. 1, 2, 3, and 4. Said plug is next inserted within the screw rim of the standard socket as far as it will go, after which, said buttons 36, and 37, are released, which first, permits said arms 1, and 2, and their contacts 6, and 7, to expand electrically connecting and attaching the latter to said screw rim; second, permits elevation of said center contact 19, rod 20, and the inner end of said cam lever 32, by means of said spring 23, until said center contact 19, engages and makes electrical contact with the center contact of said socket.

To remove said plug from said socket simply depress said buttons 36, and 37, as far as they will go and withdraw said plug.

The invention described herein may be manufactured and used by or for the Government of the United States for governmental purposes without the payment to me of any royalty thereon.

I claim:

1. An electric plug including a body, a substantially U-shaped spring member having its central portion secured within and its legs normally extending without said body, threads upon said legs, a reciprocating center contact, means mounted in the body for normally holding said center contact in extended position, a cam lever hinged to one leg of the U-shaped member for retracting the center contact, and means for operating the cam lever.

2. An electric plug including a body, a substantially U-shaped member having its legs normally separated, a reciprocating center contact, means normally holding the contact in extended position, and a cam lever hingedly carried by one of the legs of said member for closing them and retracting the center contact during the same movement of the cam lever.

3. An electric plug including a body, resilient contact arms normally separated, a center contact member, a reciprocating support therefor, means holding the support in extended position, and a cam lever hingedly carried by one of the arms and engaging the support for simultaneously closing the arms and retracting the support.

4. An electric plug including a body, normally separated resilient contact arms, a center contact, a reciprocating slotted center support, means for normally holding the center contact support in its extended position, means carried by the arms for closing them, and means controlled by one of said closing means and engaging the slot in the center support for substantially simultaneously retracting said support as the arms are closed.
